UNITED STATES PATENT OFFICE.

CHRISTOPH ADOLF GIEBELER-WANKE, OF NEW YORK, N. Y.

PHONETIC DOLL.

1,325,013.

Specification of Letters Patent.

Patented Dec. 16, 1919.

Application filed May 17, 1919. Serial No. 297,728.

To all whom it may concern:

Be it known that I, CHRISTOPH ADOLF GIEBELER-WANKE, a citizen of Germany, and a resident of the borough of Manhattan, in the city, county, and State of New York, have invented certain new and useful Improvements in Phonetic Dolls, of which the following is a specification.

The present invention relates to improvements in phonetic dolls, and has for its object to provide a doll of this character which will be simple and practical in construction, will not readily get out of order and may be operated with facility. Further objects are to provide such a doll which will be natural and life-like in appearance and in the production of the human voice, the mechanical parts being so arranged, and the superficial parts being such that the attractiveness and delicateness of the doll are in no way sacrificed. To this end I propose to provide in the present embodiment, a head formed of die cast aluminum, this head being such that it provides superior acoustic qualities, and at the same time constitutes a substantial support for the sound producing parts, and I further propose to provide a wooden or aluminum body portion within which a motor may be suitably supported. It is an object of one embodiment of my invention to provide a head which may be moved relatively to the body without disturbing the functioning of the sound producing parts, and also to provide in connection with the sound producing parts, a movable lower jaw adapted to simulate the action of the human mouth when talking or singing.

With these and other objects in view, embodiments of my invention are shown in the accompanying drawings, and these embodiments will be hereinafter more fully described with reference thereto, and the invention will be finally pointed out in the claims.

In the accompanying drawings:

Figure 1 is a vertical sectional view of a doll embodying one form of my invention, the doll being broken away below the waist; Fig. 2 is a plan view of the head with the wig removed;

Fig. 3 is a horizontal sectional view through the body portion of the doll;

Fig. 4 is a fragmentary vertical sectional view showing a portion of the head and

neck of a modified form of construction; and

Fig. 5 is a perspective view with parts broken away, showing in detail the speed controlling means of the motor.

Similar reference characters indicate corresponding parts throughout the several figures of the drawings.

Referring to the drawings, and more particularly to Figs. 1 to 3 thereof, the body 65 of the doll is formed of two halves 10 and 11 preferably of wood and glued together, the said body being provided at its upper end with a neck opening 12, slightly tapered and having an annular recess 13 surrounding the same in its upper end. The body may, if desired, be formed of aluminum, preferably die cast.

The head 14, according to the present embodiment, is formed of die cast aluminum 75 suitably painted or tinted at its outer surface, and preferably, openings 15 are provided in the ears, nose and mouth to enable the effective distribution of the sound produced within the head. Eye openings 16 are also formed in the casting, and glass, celluloid or other suitable eyeballs 17 are inserted therein. The neck 18 is tapered and fits snugly into the neck opening of the body, an annular flange 19 being provided thereon which fits into the recess 13, the head being rigidly secured to the body by means of screws 20 passing through the said flange into the body.

Within the body there is mounted a motor 90 which may be of any suitable type, and in the present embodiment comprises upper and lower supporting plates 21 and 22 connected by upright bars 23, 24 and 25 and provided with lugs 26 engaging the inner surface of the body and secured thereto by bolts and nuts 27, a tie rod 28 passing through the opposed lugs of the plate 22 engaging the sides of the body, the said tie rod rigidly supporting the motor and securely holding 100 the two halves of the body together. An upright shaft 29 is journaled between the plates and is adapted to be turned from the power of the spring contained within the casing 30 by means of a train of gears 31, 32, 33 and 34, a worm gear 35 mounted on the shaft 29 engaging the worm 36 of the governor 37 which regulates the rotation of the said shaft 29. The spring may be wound by means of a shaft 38 having a pinion 39 110

at its inner end engaging a crown gear 40 connected to the spring in the usual manner, the outer end of the said shaft being disposed in an opening 41 of the body and 5 adapted to be engaged by a crank handle 42. The disk 43 of the governor is adapted to be engaged by a stop lever 44 pivoted upon the plate 21 at 45 and adapted to be adjusted by means of a pivoted plate 46 having an inclined slot 47 engaging a lug 48 of the said lever, the said plate being adjustable by means of a rod 49 having a threaded portion 50 engaging a stud 51 provided upon the upper side of the plate 21, the said rod 10 terminating at its outer projecting end in a knurled head 52.

To the upper projecting end of the shaft 29 there is pinned the hub of an upright shaft 53 extending upwardly through the 20 body and neck into the head, where it is provided at its upper end with a circular plate 54 constituting a support for the disk record 55, the reduced extremity 56 of the said shaft extending through the said plate 25 and adapted to position the record thereon. Within the neck there is provided a bearing 57 preferably formed integral with the head and adapted to maintain the shaft 53 in upright alinement. The upper open end of the 30 head is circular and freely admits of the insertion and removal of the record.

An opening 58 is formed at the rear of the head forming a sound outlet for the enlarged end of the sound amplifying horn member 35 59 disposed within the head and pivotally and hingedly supported upon lugs 60 and 61 formed at the upper edge of the head above the said opening, a block 62 being hingedly mounted between the said lugs by 40 means of a transverse pin 63 and supporting the vertically disposed pivot rod 64 extending through the said horn member.

The reduced end of the horn is connected to the flange 65 of a laterally disposed sound 45 reproducing box 66 within which is supported a diaphragm 67, a transverse vibratory member 68 being connected to the diaphragm at its inner end and hinged at its outer end to the box as at 69, and provided intermediate 50 70 its ends with a needle support 70 to which is removably secured the needle 71 adapted to engage the grooves of the record.

The wig 72 which is preferably formed of 55 perforated aluminum adapted to permit of the free outlet of sound, is hingedly mounted upon lugs 73 formed at the front of the head, the said wig constituting a cover for the upper and rear openings of the head. The hair of the wig is secured to the aluminum base in any suitable manner.

When it is desired to renew a record or to 60 start the operation of the doll, the wig may be swung upwardly exposing the interior of the head, while the horn member and sound box may be swung out of the head about their

hinged support. A stop screw 74 is disposed at the rear of the head and is adapted to engage the periphery of the plate 54 to stop the rotation thereof by engagement therewith and to permit of its rotation when disengaged, this stop screw being conveniently accessible and normally hidden from view beneath the hair of the doll. An opening 90 is provided in the back of the body portion and is provided with a mesh-like covering 75 91, to permit of the distribution of the sound.

In Fig. 4, I have illustrated a slightly modified form of construction in which the head is movable relatively to the body, the neck 75 being a partial sphere at its lower 80 end and fitting into a similarly shaped socket 76 of the body. The shaft 77 extending upwardly from the motor through the neck, is connected by a knuckle joint 78, the axis of which is concentric to the swinging 85 axis of the head, to a shaft extension 79 journaled in a bearing 80 formed within the neck and provided at its upper end with the record supporting circular plate 81. This construction permits of movement of the 90 head to any desired position without disturbing the functioning of the sound producing parts.

The lower jaw or chin member 82 is formed separately from the head and is disposed in an opening 83 being pivotally mounted upon a transverse shaft 84 about which the same may have swinging movement and thereby simulate the movement of the human mouth in talking or singing. 100 The side portions of the member 82 are connected rearwardly of the shaft 84 by means of a transverse bar 85 provided centrally with a roller 86 engaging a lateral cam 87 disposed upon the shaft extension 105 79 and having its upper surface corrugated and engaged by the roller 86, rotation of the said cam adapted to cause oscillation of the chin member 82. The roller 86 is held in engagement with the cam by means 110 of a spring 88 tied between the transverse bar 85 and the bearing 80. It will be understood that if desired, a movable lower jaw of this type, may be provided in connection with the form of my invention shown in 115 Figs. 1 to 3.

With my improvements, a doll is provided which may be made to sing or talk in exact reproduction of the human voice. The construction is such that superior acoustic 120 qualities are provided and a very life-like rendition of the voice may be produced. The doll is of durable construction, will not readily get out of order, may be operated with facility, and the compactness of the 125 structure is such that a doll of suitable size to be handled by children may be produced.

I have illustrated and described preferred and satisfactory embodiments of my invention but it is obvious that changes may 130

be made therein within the spirit and scope thereof as defined in the appended claims.

I claim:

1. In a phonetic doll, a hollow head having a top opening, a hollow body, a motor disposed within said body, an upright shaft extending from said motor into said head, and adapted to be turned by said motor, a record supporting plate carried by said shaft within said head and accessible through said top opening, and a sound box disposed within said head and adapted to engage said record upon said support.
2. In a phonetic doll, a hollow head having a top opening, a hollow body, a motor disposed within said body, an upright shaft extending from said motor into said head and adapted to be turned by said motor, a record supporting plate carried by said shaft within said head, a horn support hinged within said head adjacent to said top opening thereof, a dependent vertical rod carried by said support, a sound horn pivoted on said rod and adapted to swing on said hinged support outward through said opening, and a sound box carried by said horn and adapted to engage the record disposed upon said support.
3. In a phonetic doll, a hollow head having a top opening, a hollow body, a motor disposed within said body, an upright shaft extending from said motor into said head and adapted to be turned by said motor, a laterally disposed record supporting plate carried by said shaft within said head, a horn support hinged within said head adjacent to said top opening thereof, a dependent vertical rod carried by said support, a sound horn pivoted on said rod and adapted to swing on said hinged support outward through said opening, and a sound box carried by said horn and adapted to engage the record disposed upon said support.
4. In a phonetic doll, a hollow metallic head open at its upper side, a hinged wig constituting a cover for said open side and adapted to be raised to expose the interior of said head, a hollow body, sound reproduction means disposed within said head, a motor disposed within said body, and means operatively connecting said motor to said sound reproduction means.
5. In a phonetic doll, a hollow metallic head open at its upper side and provided at its rear side with a sound outlet aperture, a hinged wig constituting a cover for said open upper side and adapted to be raised to expose the interior of said head, sound reproduction means disposed within said head, a sound amplifying horn therefor terminating at said aperture, a motor disposed within said body, and means operatively connecting said motor to said sound reproduction means.
6. In a phonetic doll, a hollow body, a hollow head adapted to swing on an axis at right angles to the axis of said body, a phonograph disposed within said head, a motor disposed within said body and provided with an upright shaft, and a shaft having its bearing in said head and pivotally connected at its lower end with said upright shaft on an axis concentric to the axis on which said head swings and at its upper end with said phonograph.

In testimony that I claim the foregoing as my invention, I have signed my name hereunder.

CHRISTOPH ADOLF GIEBELER-WANKE.
